UNITED STATES PATENT OFFICE

2,416,496

CONVERTIBLE FURNITURE

Donato Piciulo, New York, N. Y.

Application October 8, 1943, Serial No. 505,427

1 Claim. (Cl. 155—45)

1

This invention relates to collapsible and convertible deck or beach chairs, but more specifically to a type of chair which is convertible in conjunction with an extension piece into a sofa.

The main object of the invention resides in the provision of a chair of the above nature which in conjunction with an extension piece normally serving as a seat or foot rest, is capable of serving as a sofa, means being provided for the enclosure of the device when serving as a sofa whereby the chair can be utilized as a cabana for a single person.

A further object of the invention resides in the provision of a chair of the above nature which is light in weight, economical to manufacture, easily collapsible and extensible, sturdy in construction and which occupies a minimum of space when stored away.

These objects and other incidental ends and advantages of the invention will hereinafter appear in the progress of the disclosure and as pointed out in the appended claim.

Accompanying this specification are drawings showing a preferred form of the invention wherein corresponding reference characters designate corresponding parts throughout the several views and wherein:

Figure 1 is a side view in elevation showing the main chair portion in operative position as a seating device, the members shown in dotted lines indicating alternate positions.

Figure 2 is a side view in elevation of a collapsible chair extension in an extended position and being adapted to serve as a foot rest or seat in the position shown.

Figure 3 is a top plan view of Figure 1.

Figure 4 is a side view in elevation of the main and auxiliary chairs coupled together and in extended position serving as a sofa with the peripheral walls thereof provided with curtains or blinds to conceal the occupant.

Figure 5 is an enlarged longitudinal sectional view of a portion of Figure 4 showing coupling means for securing the main and auxiliary chair portions to the sofa.

Figure 6 is a view in perspective of a coupling member for the two chair portions.

Figure 7 is a top plan view of Figure 4.

Figure 8 is a sectional view of Figure 1 along the plane 8—8 thereof.

Figure 9 is an end view in elevation of the chair shown in Figure 1 in collapsed position.

Figure 10 is a similar end view in elevation of the auxiliary chair shown in Figure 2 in collapsed position.

2

In accordance with the invention and the preferred form thereof shown in the drawings, the collapsible deck or beach chair convertible in form to yield a sofa or sofa bed for resting or for concealed exposure to the sun is comprised essentially of a main chair and an auxiliary chair detachably securable to each other. The main and auxiliary chairs are collapsible, the auxiliary chair serving either as an independent seating means, as a foot rest or an extension of the seating surface of the main chair.

More particularly, the main chair is comprised of lateral cross members 10 and 11 pivotally secured together by a cross dowel 12, the said members being spaced by means of a spacer 12'. The lower ends of lateral cross members 10 and 11 are adapted to lie on a supporting surface and are provided with cross dowels 24 and 30. Pivoted on the cross dowel 12 and between the lateral members 10 is a back supporting member comprised of a pair of members 16 and having an upper connecting rod 17 to which is secured fabric 18 running along the length of the said side members 16 and being secured to dowel 12 by means of a pocket 12a through which the dowel 12 runs as shown in Figure 5. To maintain the back supporting member in place between the members 10 a cross dowel 15 is adapted to penetrate the members 10 and 16 for support, the said back supporting member being free to drop to a horizontal position coextensive with the seat portion of the main chair as will hereinafter be described, the openings in the members 10 and 16 receiving dowel 15 being indicated by numerals 15' and 15''.

A roof for the main chair is provided by means of a piece of fabric 13a secured to the top ends of members 10 and 11 by means of cross dowels 13 and 14, said dowels 13 and 14 being removable through corresponding openings 13b and 14b as shown in Figure 4 when the main chair is converted into a sofa. As best shown in Figures 1 and 4, the cross members 10 and 11 adjacent the upper ends are provided with reinforcing cross pieces 14c and 14a respectively. In addition, the back support also has a rear cross supporting member 16a between the lateral members 16; the said rear cross supporting member 16a being adapted to support a pair of coupling links 19 pivoted on cross dowel 12 and situated between members 16 and 11, the said coupling links 19 normally resting against member 16a when the main chair serves as such as shown in Figure 1. A hooked end 20, an opening 12'a at the opposite end and notches 21 and 22 are provided on each

of the said links 19 for engagement with other members of the main chair and the auxiliary chair when the device is converted into a sofa as will hereinafter be described.

To sustain the back supporting member when in horizontal position there is provided a frame pivoted on the lower cross dowel 24 of cross member 11, said frame being comprised of lateral members 23 secured together by a cross piece 25 and having a cross dowel 26 on the upper ends. The said frame normally rests between the lower portions of the members 11 as best seen in Figure 1 and when in supporting position for the back supporting member shown in the dotted lines of Figure 1 is secured in a withdrawn position to the members 16 by having the dowel 26 pass through openings 16b of members 16, which openings 16b are in alignment with the openings 26a of members 23. The cross members 10 and 11 are further supported by members 27 pivoted at the upper ends as at 28 to 11 and being secured together at the lower end by a cross dowel 29a, said members 27 being parallel to cross members 10 and having a reinforcing cross piece 27a therebetween. Spacers 12'a are between members 11 and 27.

Connected to the cross dowel 30 at the ends thereof are links 31 pivoted intermediate the lengths thereof to members 27 and at the upper ends thereof being provided with a cross dowel 32. A pair of similar and parallel links 37 intersect the lower parts of cross members 10 being pivoted intermediate the lower portion of cross members 10 and at the upper ends thereof secured to members 27 as through cross dowel 29, the lower ends of said links 37 carrying links 38 going in a cross direction and at the upper ends being pivoted to cross members 11.

The fabric 18 of the back supporting member is adapted to continue as indicated by numeral 35 from the cross dowel 12 along the seat portion as determined by the coplanar positions of cross dowels 29 and 32. Thus, fabric 18 is secured to cross dowels 29 and 32 by means of pockets 29b and 32c as seen in Figure 5. Disposed above seating fabric 35 is a seat member comprised of lateral frame pieces 33 pivoted at the ends thereof on cross dowel 32 and having a seat support 36 secured to the upper edges of said lateral frame pieces 33. The frame pieces 33 are provided with notches 34 to engage cross dowel 29 when the seat is in closed position as shown in Figure 1. It is to be observed that when the seat member is in closed position as shown in Figure 1, the main chair portion is prevented from collapsing in the position shown in Figure 9.

An auxiliary chair shown in Figure 2 may serve as either an independent chair separated from the main chair or as an extension for the main chair of Figure 1 or as a portion of a sofa with the main chair. The auxiliary chair, which is also collapsible, is comprised of two main lateral members 39 reinforced on the upper ends by means of a cross piece 39a and the lower ends having a cross dowel 41. Secured to 41 are a pair of cross links 40 while a pair of rearwardly and parallelly disposed links 42 are secured intermediate the length thereof to members 39. At the upper end of links 42 are disposed a pair of cross links 43 pivoted intermediate the ends thereof to links 40 while at the lower end of cross links 43 are a pair of forwardly extending link members 44 pivoted through dowel 45. The upper part of links 42 and 43 are connected by means of a dowel 43a while the lower ends of members 39

and links 40 are connected by means of a dowel 41.

The upper ends of links 44 are secured to an intermediate portion of a pair of connecting members 47. The connecting members having hooks 47a at the ends thereof are adapted to engage cross dowel 29a of the main chair. The connection between links 44 and connecting members 47 is by way of a cross dowel 46 while the upper ends of connecting members 47 are secured to the upper ends of links 43 by means of a cross dowel 48. Links 42 and 43 are secured at the upper ends by means of a cross dowel 43a, the dowels 48 and 43a preferably being in the same horizontal plane as dowel 48a connecting the main members 39.

It is to be observed that the intersecting links 40 and 42 and 43 of the auxiliary chair are pivoted at the points of intersection. A back supporting member is provided between members 39 and is in the form of a fabric strip 51 secured to the upper ends of members 39 by dowel 52, the said strip 51 having a horizontal extension 51a, said extension 51a being suitably secured to cross dowels 48a, 43a and 48. To prevent a collapsing of the auxiliary chair and to maintain the latter in extended position a seat or cover member 49a is adapted to superpose horizontal portion 51a of the fabric strip, the said cover member having lateral pieces 49 which are pivotally mounted on cross dowel 48, the said lateral pieces 49 being provided with intermediate notches 50 to engage the cross dowel 43a when in horizontal position.

When the main and auxiliary chairs are secured to each other as shown in Figure 4 the cover 43a is removed from cross piece 11 by the removal of dowel 14 thereby allowing the said cover 43a to fall over the end of the backrest 16. Side covers 53 may be provided which are adapted to engage with studs 54, 55 and 56 of members 10, 11 and 39, as shown in Figure 4. An end cover 57 may also be secured to the members 39 of auxiliary chair as by attachment to studs 56.

Thus has been described a collapsible deck or beach chair which when in extended and connected position may serve as a sofa bed on which the occupant may lie for purposes of resting or being exposed to the sun. To increase the comfort, a mattress 58 may be applied to the sofa resting surface. The sofa may serve as an independent cabana wherein the occupant may dress or undress by the use of the peripherally disposed cover members.

I wish it understood that minor changes and variations in the integration, material and location of parts of the invention may all be resorted to without departing from the spirit of the invention and the scope of the appended claim.

I claim:

A chair comprising a pair of laterally spaced side frames, each including a plurality of crossed links pivotally connected in series in the manner of vertically positioned lazy tongs, means including cross-dowels and reinforcing cross-members joining said side frames to each other and holding the same in spaced relation, a link of each side frame correspondingly positioned one to the other being extended upwardly to form a back frame for the chair, one of said cross-dowels connecting the upper forward ends of said side frames, a second cross-dowel connecting said side frames rearwardly of said first cross-dowel, and a third cross-dowel connecting the extended back frame links, all said cross-dowels being in hori-

zontal alignment, a seat member including a seat frame pivoted to said first mentioned cross-dowel and notched to engage said second and third cross-dowels to hold the lazy-tongs extended, a back rest pivoted upon said third dowel to swing from a raised position between said extended back frame links to a lowered position in alignment with the extended seat member, means carried by said back frame links for detachably securing and supporting said back rest in raised position, a supporting frame pivoted to the lower rear ends of said side frames to swing rearwardly therefrom and means carried by said supporting frame for engaging and detachably securing said back rest to support the same in lowered position.
